PROCESS FOR MAKING WALLBOARD.

Application filed April 20, 1926. Serial No. 103,393.

The present invention relates to a process for making wallboards suitable for use on the walls or ceilings of a room and having good heat insulating qualities. It is made from 5 a mixture of a filler and a binder which puffs into a porous rigid coherent mass under the action of heat and is provided with a facing of other material.

It is an object of the present invention to 10 produce a flat surface on an improved wallboard or other flat molded product composed for the most part of inorganic material, that product being light in weight, cheap in cost, and having a high porosity, and, 15 consequently, a low thermal conductivity. The wallboards of the present invention may be of the thickness and of the size of ordinary paper wallboards, and have a facing of paper, cloth, or other facing material on one or both 20 sides.

As set forth in Weiss and Norris application Serial No. 720,511, filed June 17, 1924, (now Pat. No. 1,628,206, granted May 10th, 1927) when an intumescent binder such as a 25 soluble alkali silicate, hide glue or cornstarch is mixed with a filler and subjected to the action of heat, the mass expands or puffs up and ultimately hardens into a firm strong body filled with air cells or pores. In Serial 30 No. 720,510, filed June 17, 1924, Weiss and Norris disclose a method by which the mixture of alkali silicate and filler may be used in the manufacture of wallboards. About 35 one part alkali silicate, such as sodium silicate, having a density of about 42.5° Bé. is intimately mixed, as in a mixer, with about two parts of a filler such as pulverized limestone, which may be dolomitic in character, to a doughlike consistency. A soap, or a 40 fatty acid, such as oleic acid, which forms a soap with the soda in the sodium silicate, may be added in small amounts to aid in securing a better puffing action. When the board or panel is to have a paper facing on both sides, the dough or mix thus formed is 45 spread upon a sheet of paper either in an even layer or as stripes, (an even layer having a depth of $\frac{1}{16}$ " to $\frac{1}{8}$ " will form a board approximately $\frac{5}{16}$ " in thickness). A second sheet of paper is placed on top of the dough so 50 that the product in its green condition consists of two sheets or strips of paper with a layer of dough between. The paper may be an ordinary chipboard rather heavily sized

so that it will be water-resistant and tough, 55 although, of course, other kinds of paper and facings may be used. The green sheet is then slid between two steam heated iron platens spaced a distance equal to the thickness desired for the finished board, say, for 60 instance, $\frac{3}{8}$ ". The steam platens may be heated with steam at a pressure of about 25 to 100 pounds. The application of heat of about that temperature causes the dough to 65 puff up and force the upper sheet of paper or other facing against the upper platen. During this heating process water is driven off from the mixture, particularly along the edges of the board. In about thirty minutes 70 the dough has puffed sufficiently and sufficient moisture has been driven off so that the board in its puffed and porous condition is rigid enough to be removed from the platens.

The tenacity with which the composition 75 sticks to the paper sheets is one of the important characteristics of the paper faced board, for there is no tendency for the sheets to blister or strip away from the mineral filler. The paper is very tenaciously held, 80 thereby strengthening the board and adding to its resistance against chipping during shipment, or while nails are being driven through it. In cross section the inorganic core of the finished board is not unlike in appearance the cross section of a loaf of fine 85 grained bread.

Although the Weiss and Norris method described results in wallboards which have flat surfaces if the paper is of sufficient thickness, as described in a copending application, 90 Serial No. 720,510 filed June 17th, 1924, it is often desirable to make wallboards with a facing of paper of a lesser thickness. For a $\frac{3}{8}$ " board weighing about 1200 pounds per 95 1000 square feet if a paper less than .037 inch in thickness is used for a facing material the surface of the boards will usually have small pockets or depressions which makes them unsaleable, except as seconds. The depressions also may be in the form of waves. My novel method overcomes these difficulties and it is possible to make wallboards with a flat surface without pockets, depressions or waves.

Other objects and advantages of the present invention will become clear from the following description taken in conjunction with the accompanying drawings, all of which are diagrammatic in character.

Fig. 1 is a fragmentary section of a wallboard and the heating platens showing one method of sealing an edge of the board during the heating operation;

5 Figs. 2, 3 and 4 are similar views illustrating modifications of the apparatus;

Fig. 5 is a fragmentary section showing the edge of a board bound with kraft paper and ready for trimming.

10 During the puffing operation, steam is driven off from the doughlike mix. This steam comes from the water in the silicate solution and it is the expansion of the water into steam that probably causes the cellular structure of the wallboard. While, no doubt a very slight steam pressure is generated in the interior of the board due to the friction of the cellular passages to the passage of the steam from the interior to the outside edges 15 of the board, this pressure is not enough to prevent the formation of the pockets, depressions and waves which probably result from the distortion of the paper due to the presence of unevenly distributed moisture and heat. By increasing the steam pressure on the interior surface of the facing it becomes possible to force the facing against the platen and keep it flat until the mix hardens and the paper or other facing material becomes thoroughly dried. The steam pressure must be great enough to counteract the warping tendency of the paper. Since the steam is generated during the puffing action at the place where the pressure is needed it becomes necessary to retain the steam on the interior of the 20 puffing and hardening wallboard. Several methods may be used. Figures 1 to 5 show different methods for maintaining the steam pressure inside of the wallboard. All depend upon closing the edges of the board to prevent the escape of the steam.

In Fig. 1 platens 1 are heated by steam, oil or other media in the hollow spaces 2. The wallboard consists of the mix 5 with the adhering facings 4. The facings 4 project beyond the mix 5 and extend beyond the platens as shown. When the green board is in place the metal strip 3 with chamfered edges moves forward between the upper and lower projecting facings 4, forcing them against the chamfered corners of the platens 1 and effectively sealing the edges of the board. The other edges of the board are similarly sealed. When the heat from the platens evaporates the water in the mix and puffs it, pressure is generated inside of the board, forcing the facings against the plane surfaces of the platens, and preventing wrinkles and pockets from forming. The excess steam may be relieved from the board interior at any time by slightly loosening the steel strips.

Fig. 2 illustrates a modified method by which a steel frame 3 may be used to maintain the steam pressure inside of the wallboard.

65 A steel frame of suitable dimensions, usually

slightly smaller than the platens, is laid on the green board. The frame may be made of round or square steel rods or other suitable material. The upper platen is allowed to rest directly on this frame 3. The doughlike mix is pinched away at this point so that the upper and lower facings 4 touch and form a tight seal, thus preventing the escape of steam. The thickness of the resulting board is determined by the dimensions of the rod which constitutes the frame, plus the thickness of the two facings. A $\frac{3}{8}$ inch board with .032 inch facings requires a $\frac{1}{16}$ inch rod. The steam in the board is relieved by raising the top platen slightly. The steel frame has the disadvantage of being difficult to handle due to its flexibility. It is difficult to place exactly as desired on the green board between the platens.

70 Figs. 3 and 4 show my preferred method for developing a steam pressure in the inside of the wallboard. In Fig. 3 the strip of steel 3 or other suitable metal is fastened to either the top or bottom platen 1 and acts in the same manner as the steel frame 3 of Fig. 2. The steel strip may be inset and fastened by screws or by welding to the platen. An alternative is shown in Figure 4 where one-half of the steel strip 3 is fastened to the top and bottom platens respectively. The last 75 method has the advantage that the amount of board trim to the top of the shoulder 7 is smaller than when the single strip is used. The steam may be relieved by raising the top platen slightly.

80 The methods described for maintaining the steam pressure, when used with paper facings of .030 to .035 inch thickness, require trimming about $\frac{3}{4}$ to 1 inch from the edge of the board. The thick papers result in a longer shoulder than the thin papers due to the greater flexibility of the latter. The amount of trim may be cut to a minimum by utilizing the flexibility of a thin tough paper such as kraft at the edges of the board shown in Fig. 90 5. This illustrates a board after puffing. A strip of thin tough paper 6 is pasted on the interior of the facings 4 so that the strip projects beyond the edge of the facing far enough to allow the steel strip or frame 3 in Figs. 105 2, 3 and 4, to press it upon the lower strip and retain the steam within the board. Instead of forming a long shoulder as in Figs. 110 2, 3 and 4, the steam pressure results in a square shoulder as shown in Fig. 5. This results in a minimum amount of trim at 7 and also reinforces the facing at the edge where additional strength may be utilized, and binds the edge of the board. This method is especially adapted to the maintaining of 115 steam pressure in a continuous machine, in which only two sides of the board have to be closed.

120 By maintaining a steam pressure in the interior of the board having a thin facing 130

it becomes possible to develop designs in relief on the surface of the board. The paper, which becomes somewhat plastic when heated in the presence of the steam from the green mix, may be molded to some extent. If designs replace the plane surface of the platen and a steam pressure is maintained inside of the board, the design on the platens will be found to be in reversed relief on the surface 10 of the board. The advantage of this feature is apparent to those skilled in the art, especially for the marking of the surface in imitation of tile, brick, etc.

The expressions "closing the edges of the 15 board" and "temporarily sealing" used in the claims are not intended to cover a mould of the ordinary type in which the edges of the board would be closed by the side walls of the mould but are limited to the use of additional closing means forming no part of the 20 mould proper.

I claim:

1. A method of making a lined wall board consisting essentially of heating a mixture of 25 an intumescent plastic and a filler while confined between paper facings to puff and solidify the mixture and cause it to adhere to the facings, and closing the edges of the board during the heating operation to maintain a steam pressure upon the inner surfaces 30 of the liners during the puffing operation.

2. A method of making a lined wall board consisting essentially of heating a mixture of 35 an intumescent binder and a filler while confined between paper facings with the outer surfaces of the facings in contact with plane surfaces to puff and solidify the mixture and cause it to adhere to the facings and closing the edges of the board to maintain steam 40 pressure on the inner surfaces of the facings during the puffing operation.

3. A method of making a lined wall board consisting essentially of heating a mixture of 45 an intumescent binder and a filler while confined between paper facings with the outer surfaces of the facings in contact with plane surfaces to puff and solidify the mixture and cause it to adhere to the facings and temporarily sealing some of the edges of the 50 board to develop a steam pressure upon the inner surfaces of the facings during the puffing operation.

4. A method of making a lined wall board consisting essentially of heating a mixture of 55 an intumescent binder and a filler while confined between paper facings with the outer surfaces of the facings in contact with plane surfaces to puff and solidify the mixture and cause it to adhere to the facings and holding 60 the upper and lower facings together during the puffing operation to maintain steam pressure upon the inner surfaces of the liners until the puffing operation is complete.

5. A method of making a lined wall board consisting essentially of heating a mixture of 65 an intumescent binder and a filler while confined between paper facings with the outer surfaces of the facings in contact with plane surfaces to puff and solidify the mixture and cause it to adhere to the facings, closing the 70 edges of the board to maintain steam pressure on the inner surfaces of the facings during the puffing operation and ultimately trimming away excess material from the edges that have been thus closed. 75

6. A method of making a lined wall board consisting essentially of heating a mixture of 80 an intumescent binder and a filler while confined between paper facings to puff and solidify the mixture and cause it to adhere to the facings, said facings being in contact with heated, flat platens, and holding together the upper and lower facings along their edges to develop such steam pressure upon the inner surfaces of the liners during the puffing operation as will hold the outer surface of each 85 liner in close contact with its adjacent platen.

7. A method of making a lined wall board consisting essentially of placing a mixture of 90 an intumescent plastic and a filler between paper facings and heating the same by placing it between flat platens, securing a flexible paper strip along the edge of one liner and pressing said paper strip against the other liner to temporarily seal the edges of the 95 board and develop such steam pressure upon the inner surfaces of the liners as will insure close contact between the outer surface of each liner and its adjacent platen.

8. A method of making a lined wall board 100 having surface designs in relief consisting essentially of placing a mixture of an intumescent binder and a filler between paper liners, placing the liners and mixture between hot platens having the desired designs shaped 105 therein and temporarily sealing the edges of the board to develop and maintain such steam pressure in intumescent material as will force the liners into close contact with the platens and insure reproduction of the 110 designs formed therewith.

9. A method of making a lined wall board 115 having surface designs in relief consisting essentially of placing a mixture of an intumescent binder and a filler between paper liners and placing the liners and filler between hot platens having the desired designs shaped 120 therein, and temporarily holding the liners in contact with one another to develop upon the inner surface of the liner enough steam pressure to force the liner in close contact with the platens, thereby receiving therefrom an imprint of the design carried by the platen.

In testimony whereof I affix my signature.

OLIVER W. STOREY.
